Frank Warren

UNITED STATES PATENT OFFICE.

ANDREW NILAND, OF BREMERTON, WASHINGTON, ASSIGNOR OF ONE-THIRD TO MARTIN A. EK AND ONE-THIRD TO A. H. FINDLEY, BOTH OF BREMERTON, WASHINGTON.

HAIR-CLIPPING ATTACHMENT FOR VIBRATORS.

1,329,675.

Specification of Letters Patent.

Patented Feb. 3, 1920.

Application filed February 5, 1919. Serial No. 275,278.

To all whom it may concern:

Be it known that I, ANDREW NILAND, a subject of the Government of Finland, residing at Bremerton, in the county of Kitsap 5 and State of Washington, have invented a certain new and useful Improvement in Hair-Clipping Attachments for Vibrators, of which the following is a specification.

My invention relates to improvements in hair clipping attachment for vibrators and the object of my invention is to provide hair clippers of simple, strong and efficient construction that may be quickly and easily attached to an electric vibrator of a type commonly used in barber shops, the clippers being adapted to be driven by the vibratory movement of the vibrator.

My invention consists in the novel construction of the hair clippers, and in the 20 novel adaptation and combination of the same with a vibrator as will be more clearly hereinafter described and claimed.

I accomplish this object by devices illustrated in the accompanying drawings, 25 wherein—

Figure 1 is a view in side elevation of clippers constructed in accordance with my invention as said hair clippers may appear when attached to a vibrator;

Fig. 2 is a plan view of the hair clippers as they might appear when detached from the vibrator;

Fig. 3 is a detached view in front elevation of the hair clippers; and Fig. 4 is a view 35 in cross-section on broken line 4, 4 of Fig. 2.

Referring to the drawings throughout which like reference numerals indicate like parts, the numeral 5 designates an electric vibrator which is of a well known type and 40 which is provided near its forward end with a shank 6 that is adapted to have a vibratory motion imparted thereto.

My invention resides in the provision of hair clippers that are adapted to be secured 45 to the vibrator 5 and connected with the vibratory shank 6 in such manner that the vibrations of the shank 6 will impart the desired reciprocating motion to the hair clippers.

The hair clippers comprise a base portion 50 or foot 7 that is provided on its front edge with cutting teeth 8 of the form common to hair clippers and an upper reciprocable clipping member 10 that is disposed on

the top side of the base portion 7 and is provided on its front edge with teeth 11 that are adapted to be moved, or reciprocated crosswise with respect to the teeth 8 in such manner that hair which enters between the teeth of the clipping member 10 and the 60 teeth of the base member will be severed.

The clipping member 10 is provided with a notch or recess about midway its length for the reception of the square end 13 of a shank 14 that is adapted to screw into the shank 6 of the vibrator.

The clipping member 10 is guided for reciprocation on the top of the base member 7 by two stud pins 15 that are rigid with the base member 7, and project upwardly 70 through slots 16 provided in the clipping member 10 as more clearly shewn in Fig. 4 and such clipping member 10 is held in close contact with the base portion 7 by flat springs 17 that are placed on the studs 16 75 between nuts 18 and the top of the clipping member 10.

The pressure of the springs 17 may be varied by adjusting the nuts 18.

The base member 7 is rigidly secured to a 80 plate 20 which is rigidly secured to a split ring 21 that is adapted to encircle the body portion of the vibrator 5 and to be rigidly secured thereto by a bolt 22 that passes through upturned ends 23 that are formed 85 at the upper side of the ring 21. The plate 20 and rings 21 thus constituting simple and easily detachable means by which the hair clippers are rigidly secured to the vibrator.

In the operation of my invention the motion of the vibrator shank 6 will reciprocate the upper plate 10 of the hair clippers with a stroke and at a desired speed whereby hair may be cut without pulling the same.

Obviously changes may be made in the 95 form and arrangement of parts of my invention without departing from the spirit thereof.

What I claim is:

1. An attachment for a vibrator comprising 100 hair clippers having a movable part arranged to be connected with the vibratory shank of the vibrator and another part arranged to be rigidly connected with the frame of the vibrator.

2. The combination with a vibrator having 105 an external frame and provided with a vibratory shank, of hair clippers comprising

ing a lower toothed member arranged to be rigidly connected with the frame of said vibrator and an upper toothed member arranged to be connected with the vibratory shank of said vibrator.

3. A hair clipping attachment for vibrator comprising a toothed base member, means for rigidly securing said base member to the body of a vibrator, an upper toothed clipping member, means for guiding said upper toothed clipping member for recipro-

cation over said base member, resilient means for holding said upper toothed clipping member in contact with said lower member and a shank for connecting said upper clipping member to the vibratory shank of a vibrator.

In witness whereof, I hereunto subscribe my name this 29th day of January, A. D. 1919.

ANDREW NILAND.
